(57) **CLAIM**

The ornamental design for a spline jig as shown and described.

DESCRIPTION

FIG. 1 is a front, top, right side perspective view of a spline jig in accordance with my design;

FIG. 2 is a front elevation view of the spline jig as shown in FIG. 1;

FIG. 3 is a rear elevation view of the spline jig as shown in FIG. 1;

FIG. 4 is a left side elevation view of the spline jig as shown in FIG. 1;

FIG. 5 is a right side elevation view of the spline jig as shown in FIG. 1;

FIG. 6 is a top plan view of the spline jig as shown in FIG. 1; and,

FIG. 7 is a bottom plan view of the spline jig as shown in FIG. 1.

The broken lines shown in the drawings represent environmental subject matter and portions of the spline jig that form no part of the claimed design.
